METHOD AND APPARATUS FOR
FORMING TABLETS

Allan M. Raff, Elkins Park, Pa., assignor to Smith Kline & French Laboratories, Philadelphia, Pa., a corporation of Pennsylvania

Filed June 6, 1962, Ser. No. 200,463
4 Claims. (Cl. 107—54)

This invention relates to improvement in a method and apparatus for making tablets.

Conventionally, in the formation of tablets such as, for example, pharmaceutical tablets, a lubricant is added to the tablet mix which is then placed in a mold cavity and compressed with punch means. The tablet lubricant is necessary to reduce tool wear and to insure that the thus formed tablet will not adhere to the mold or punch means and can hence be readily ejected. The presence of the tablet lubricant, however, causes a reduction of the cohesiveness of the tablet mix which in turn for a given compressional pressure causes a reduction in desired tablet hardness. Of particular importance with respect to the pharmaceutical tablets, the presence of the tablet lubricant requires the use of increased pressure to achieve the desired tablet hardness and this in turn results in an undesirable increase in the time that it takes the tablet to disintegrate after it has been ingested.

It is, therefore, the broad object of this invention to provide an apparatus and method giving increased tablet hardness for a given compressional force and to reduce the tablet disintegration time by the method and apparatus of this invention.

In accordance with the method of this invention, the general procedure of forming a tablet by first forming a particular tablet mix, introducing the tablet mix into the mold of a tabletting machine and compressing the mix into a tablet with punch means are employed. However, rather than including the necessary lubricants (as distinguished from agents aiding free flow of the mix) in the tablet mix in the conventional manner, a tablet lubricant is periodically sprayed on the punch means and the interior of the mold. This permits the elimination of all of the tablet lubricant from the tablet mix. Only sufficient lubricant need be sprayed on to provide a substantial covering of the parts which come into contact with the tablet mix. It has been found satisfactory to carry out the spraying once for each about 250 to 300 cycles of operation. While the spraying may be carried out more frequently, it is generally not necessary to do so.

The method of this invention is useful with any material which is tabletable by heretofore known methods. Typical, for example, are drugs such as dextroamphetamine sulfate, phenobarbital, chlorpheniramine maleate, ascorbic acid, atropine sulfate and potassium penicillin which may be combined with other ingredients, for example, fillers such as lactose, dry starch, powdered sucrose, dicalcium phosphate and calcium sulfate dihydrate.

Any of the heretofore known large number of tablet lubricants can be employed in this invention. Thus, for example, powder lubricants, for example, pharmaceutically acceptable metallic soaps such as magnesium stearate or calcium stearate, stearic acid and talc can be employed. Similarly, liquid lubricants, such as butyl stearate or liquid petrolatum may be used. The lubricant advantageously is applied in an aerosol in which the propellant gas may be any of the pharmaceutically acceptable gases frequently employed in the aerosol type dispensers such as, for example fluorinated hydrocarbon derivatives of short chain aliphatic organic compounds such as dichloro-difluoromethane, dichlorotetrafluoroethane, octafluorocyclobutane. Further exemplary are com-

ponents of the apparatus and methods of this invention. The apparatus includes a frame 4 having a base 6, a stationary table 8, a rotating head 10, and a feed frame 38. The feed frame 38 is provided with an aerosol container 50 which contains a tablet lubricant and a propellant gas. The aerosol container 50 is connected to a control valve structure 52 which can be used to control the flow of the aerosol to line 54 manually when the timer to be described is inoperative. Line 54 contains a solenoid valve indicated at 55. Valve 55 is connected to a timer schematically indicated at T by

2

5 The method and apparatus of this invention will be further clarified by a reading of the following description in conjunction with the drawings:

FIGURE 1 is a perspective view of a rotary tabletting machine incorporating the improvement of the invention;

FIGURE 2 is a plan view partly broken away of the feed frame of the machine of FIGURE 1, incorporating the spraying apparatus in accordance with the invention;

FIGURE 3 is a development of the cam tracks which control movement of the punches of the machine of FIGURE 1; and

FIGURE 4 is a vertical section through a pair of adjacent dies illustrating the spraying action of the apparatus of this invention.

Referring to FIGURE 1, a rotary tablet pressing machine 2 has a frame 4 provided with a base 6. Mounted on frame 4 is a stationary table 8 and a rotating head 10, which rotates clockwise as viewed looking down on it. As best seen in FIGURE 4, head 10 is constructed so as to form outwardly extending rings 12, 14 and 16. Ring 12 is provided with opening 17 to accommodate upper punches 18. Ring 14 is provided with openings 21 to accommodate molds 22. Ring 16 is provided with openings 23 to accommodate lower punches 24. As best seen in FIGURE 3, upper punches 18 and lower punches 24 are actuated by a cam track 28 and a cam track 30, respectively or by compressing rolls 32 and 34, respectively.

FIGURE 3 shows a step by step sequence of the operation of punches 18 and 24, the degrees marked on the top being arbitrarily chosen to show the synchronized action of the parts. At 0°, lower punch 24 starts down opening the mold cavity, at about 75°, powder is supplied to the molds for the filling operation. The lower punch is then elevated to remove excess powder which is scraped off. The lower punch is then again lowered until it is elevated by compressing rollers 34 at which time upper punch 18 which has been elevated is lowered by compressing roller 32 to form the tablet. At 330°, the tablet has been lifted out of the mold and rides off at C in FIGURE 1.

Referring now to FIGURE 2, a feed frame 38 is mounted so as to overlie ring 14 and is provided with walls indicated at 40, 41, 42, and 43 to form the conventional feed frame grid. A supply hopper 44 is mounted for discharge of the tablet mix onto ring 14 between walls 40 and 41.

As just described, the rotary tablet compressing machine is well-known to the art and in wide commercial use today and hence need not be described in any greater detail. For a description of the said tabletting machine, reference may be had, for example, to United States Patent No. 2,043,086, issued June 2, 1936.

Referring now to FIGURE 1, an aerosol container 50 is provided to contain the tablet lubricant and the propellant gas of the aerosol. Container 50 is provided with a control valve structure indicated at 52 which can be used to control the flow of the aerosol to line 54 manually when the timer to be described is inoperative. Line 54 contains a solenoid valve indicated at 55. Valve 55 is connected to a timer schematically indicated at T by

a line 56 and is connected to ground by a line 57. Timer T is supplied with power by line 58 and is connected to ground by a line indicated at 60. Timer T can be of any well known type of timer providing an electrical on-off time cycle and will be set to open valve 55 periodically for the time period required for a complete revolution of head 10. While as previously indicated, the frequency of the opening of valve 55 may vary, timer T will be set to open valve 55 at least once for each about 250-300 revolutions of head 10. Line 54 discharges into a manifold indicated at 64 (see FIGURE 2) which is secured to frame 38 by welding. Lines 66 and 68 connect manifold 64 to nozzles 70 and 72, respectively. Nozzles 70 and 72 are located on the circumference containing the center line of punches 18 and 24 and on this circumference are located apart the distance separating two adjacent molds 22. The location of nozzles 70 and 72 with relation to the sequential operation of the tabletting machine is shown in FIGURE 3 where the position of these nozzles are indicated by the circles indicated at 70 and 72, respectively. As shown best in FIGURE 4, nozzle 70 is directed downwardly so as to spray the gas-lubricant aerosol into molds 22 and nozzle 72 is directed upwardly so as to direct the spray against punches 18.

It is advantageous to have the punches and interiors of the molds finished with porous chromium plating which retains the lubricant in an improved manner making it possible to apply the lubricant less frequently.

With reference to the previous description of the operation of the tabletting machine and the showing of FIGURE 3, it will be seen that nozzle 72 is positioned so as to spray punches 18 when they are in their elevated position. Similarly, nozzle 70 is positioned to spray downwardly into molds 22 when punches 24 are fully retracted. It will be appreciated that both spray nozzles are positioned in advance of wall 40 of frame 38 and hence in no way interfere with the filling of mold 22 with the tablet mix.

In operation, the machine 2 is run until timer T is operative to open valve 55 to actuate spraying of the gas-lubricant aerosol through nozzles 70 and 72, timer T keeping valve 55 open during one complete revolution of head 10. The tablet mix free of lubricant is then supplied by means of supply hopper 44 and tablets are produced in the conventional manner. After, for example, 250 revolutions of head 10, timer T actuates valve 55 to spray the aerosol during another complete revolution of head 10 during which revolution tablets will continue to be formed. The operation is repeated until the desired number of tablets are formed.

From the above it will be understood that the method of this invention comprises the steps of forming a tablet in a tablet compressing machine of the type having a mold and punch means adapted to cooperate with the mold wherein the punch means and interior of the mold are periodically sprayed with a tablet lubricant in a spray.

It is not desired to be limited except as set forth in the following claims.

What is claimed is:

1. The steps in the method of forming a pharmaceutical tablet in a tablet compressing machine of the type having a mold and punch means adapted to cooperate with the mold, comprising periodically spraying the punch means and the interior of the mold with a pharmaceutical tablet lubricant in an aerosol spray, repeatedly introducing a pharmaceutical tablet mix substantially free of tablet lubricant into the mold and compressing the mix with the punch means to form a tablet.
2. In a rotating tabletting machine having means for rotating a plurality of molds and a plurality of punches for cooperation with said molds, means to feed a tablet mix into the molds, means to retract the punches to permit the feeding of material into the molds and means to advance the punches to compress material fed into the molds, the improvement comprising porous metal plating on the molding surfaces of the punches and the molds for the storage of a lubricant, means including a valve to spray a tablet lubricant on the said molding surfaces with the punches retracted and control means including a timer to maintain the valve normally closed during the rotation of the molds and punches and to periodically open said valve for at least one complete rotation of the molds and punches.
3. The improvement of claim 2 in which the metal is chromium.
4. In a rotating tabletting machine having means for rotating a plurality of molds and a plurality of sets of upper and lower punches for cooperation with said molds, means to feed a tablet mix into the molds, means to retract the punches to permit the feeding of material into the molds and means to advance the punches to compress material fed into the molds, the improvement comprising porous chromium plating on the molding surfaces of the punches and the molds for the storage of a lubricant, means including a valve and a pair of nozzles positioned between the plane of the upper ends of the molds and the plane of the retracted lower ends of the upper punches to spray a tablet lubricant on the said molding surfaces with the punches retracted and control means including a timer to maintain the valve normally closed during the rotation of the molds and punches and to periodically open said valve for at least one complete rotation of the molds and punches.
